CLAIM

The ornamental design for a modular shelving interconnection assembly, as shown and described.

DESCRIPTION

FIG. 1 is an isometric view of a modular shelving interconnection assembly, showing my new design;

FIG. 2 is a left side view of my design as depicted in FIG. 1;

FIG. 3 is a top view of my design as depicted in FIG. 1;

FIG. 4 is a right side view of my design as depicted in FIG. 1; and,

FIG. 5 is front view of my design as depicted in FIG. 1. The broken lines in all of the Figures are for environmental purposes only and form no part of the claimed design.
